Samuel Wilson's Design for Pantor Stove

Patented Mar. 5, 1861.

Samuel Wilson

At C. Hall Jr.
J. H. Chapman

Des. 1487

Whole No. 1487.

Gardner Gilson of Boston, Mass
Letters Patent No. 122, dated Nov. 5, 1861.

The schedule referred to in these Letters Patent and making part of the same.

To all persons to whom these presents shall come:

It is known that I, Gardner Gilson, of Boston in the County of Suffolk, and State of Massachusetts, have invented or produced a new and ornamental design or configuration, for a Parlor Stove, and I do hereby declare the same to be fully described in the following specification, and represented in the accompanying drawing, which denotes a perspective view of a stove, having the design or configuration constituting my invention.

My design has reference only to the base portion of the stove, the cap plate, the fern, the fuel and ash pit door frames, the register and the legs of the stove.

In the drawings, A, denotes the base portion of the stove, or that part on which the body B. of the stove, and the funnel C. rests. This base part is of a flaring bell shape, in vertical section, and has a curved irregular outline in horizontal section: D. is the fern. E, the top plate. F and G, the door frames; I and J, the doors, and H, H, H, the legs of the stove and K, the register.

Around the entire lower part of the base portion of the stove, a series of pendants, a. a. a. are disposed, while around the top part of such portion, and near the body of the stove, another series of drops or pendants, b. b. b. are arranged. Between the said two series of pendants, a wreath or chain c. of stellated flowers, or spear shaped leaves are arranged, each group alternating with a trefoil, or three leaved flower as represented in the drawing.

The register K, is of a circular form and has its fronto pyramidal openings surrounded by an engine chased ground.

Des. 1487

The legs H.H.H. are of a curved scroll form in vertical section, and each has a pistol extending upward from the scroll, and surrounded on each side by a spreading leaf. F. is the fuel door frame, which is of a frusto pyramidal form, and is ornamented with a series of leaves, having their bases disposed near the body of the stove, and their apices extending toward the door. G. represents the ash pit door frame, the same also having a series of similar shaped leaves disposed upon it, in manner as shown. E. is the cap plate of the stove, the same having a series of leaves, d. d. & e., formed entirely around the edge of its top surface, while the part above it is surmounted by a wreath or chain of laminated fruit, flanked by spear shaped pellets, a pendant hanging down between each two of said growths. D. is the urn, the base portion of which has a series of leaves extending downward from its rim, of the form as shown, while the shaft has another series of leaves arranged upon it.

I claim the design of the base A, the door frames F. and G., the cap plate E., the legs H.H.H. the register B., and the urn D., the same being formed and ornamented in manner as shown in the drawings.

Witnesses.
